US00D792847S

(12) **United States Design Patent** (10) **Patent No.:** **US D792,847 S**
Stone et al. (45) **Date of Patent:** **** Jul. 25, 2017**

(54) **ULTRACAPACITOR MODULE**

- (71) Applicant: **Maxwell Technologies, Inc.**, San Diego, CA (US)
- (72) Inventors: **Kevin T. Stone**, San Diego, CA (US); **Steven Watts**, San Diego, CA (US); **Steven Shelton**, Escondido, CA (US); **Ishmael Rahimian**, San Diego, CA (US)
- (73) Assignee: **Maxwell Technologies, Inc.**, San Diego, CA (US)
- (**) Term: **15 Years**
- (21) Appl. No.: **29/583,742**
- (22) Filed: **Nov. 8, 2016**

Primary Examiner — Elizabeth J Oswecki*(74) Attorney, Agent, or Firm* — Knobbe Martens Olson & Bear LLP(57) **CLAIM**

The ornamental design for an ultracapacitor module, as shown and described.

DESCRIPTION

FIG. 1 is a top perspective view of an ultracapacitor module showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings form no part of the claimed design.
